UNITED STATES PATENT OFFICE.

WILLIAM WENDERHOLD, OF NEW YORK, N. Y., ASSIGNOR TO CRU PATENTS CORPORATION, A CORPORATION OF NEW YORK.

FILM-TAKE-UP DEVICE.

1,275,636.

Specification of Letters Patent. Patented Aug. 13, 1918.

Application filed July 20, 1915. Serial No. 40,981.

To all whom it may concern:

Be it known that I, WILLIAM WENDERHOLD, a citizen of the United States, residing at New York city, in the county and State of New York, have invented certain new and useful Improvements in Film-Take-Up Devices, of which the following is a description.

This invention relates to a film winding device, also called a take-up device, and particularly to the mechanism which controls the speed of the take-up reel.

It is well known that on a take-up reel the diameter constantly increases and it is therefore necessary to change the speed of the reel or as is usually done, a friction drive is provided which allows the reel to slip as needed.

The object of my invention is to provide a variable speed drive for a take-up reel, said drive being controlled by the travel of the film before the film reaches the periphery of the reel.

Referring to the drawings,

Figure 1 is a side view showing a reel of film in its container below the partially shown kinetoscope.

Fig. 2 is a side view showing the driving mechanism.

As shown in Fig. 1, the film F is delivered by the lower feed sprocket 1 in the kinetoscope A past the roller 2 on to the reel 3. Between the reel 3 and the sprocket 1 I mount an auxiliary film guide arm mounted on shaft 5. On this arm I provide two rollers 6 and 6^a, between which rollers the film passes, the film being pulled to the reel 3 in a straight line. As the reel of film gets larger in diameter the position of this straight line described changes and the film forces the two rollers 6 and 6^a to travel since their support 4 is mounted pivotally on the shaft 5. This is the point from which I receive the force to operate the variable speed in proportion to the size of the circumference of the film already wound.

In Fig. 2 the shaft 5 carries an arm 7 which will move the friction pulley 8 in proportion to the movement of the support 4 (Fig. 1). The pulley 8 is slidably mounted on shaft 9 and is provided with a key slidably engaging the shaft. This shaft 9 is mounted in the supports 10 and 11 which are fastened to the general container frame 12.

The friction pulley 8 drives a friction plate 13 which is mounted on the shaft 14, which also carries on the inside of container frame 12 the reel 3 (as shown in Fig. 1). On shaft 14 is loosely mounted a bevel gear 15 which is fastened to the pulley 16. The bevel gear 15 drives the bevel gear 17 on shaft 9 on which shaft the sliding pulley is mounted. The bevel gear 15 and pulley 16 are driven by the belt 18 from a pulley 19 mounted on the kinetoscope mechanism. The shaft 14 is mounted in the frame 12 and 12^a and carries the film reel 3 and the disk 13. It will be seen therefore that the driving speed is varied by the movement of the arms 4 and 7.

The device can be changed without departing from the principle of operation herein described, and the invention chiefly consists in operating the variable speed drive by the change in the line of position of the film between the kinetoscope and the film reel.

What I claim as my invention is:

1. In a motion picture apparatus or the like, the combination with a film take up reel, friction devices for driving said film take up reel, a movable guide for delivering the film to said reel, means for moving said guide a distance in proportion to the like, the combination with a film take up reel, friction devices for driving said film take up reel, a movable guide for delivering the film to said reel, means for moving said guide a distance in proportion to the increase of diameter of said reel as the film winds thereupon, and means controlled by the movement of said guide for controlling the position of said friction devices to thereby control the speed of rotation of said reel.

2. In a motion picture apparatus, a film take up reel, a guide arm for the film, a friction disk for driving said reel, means for controlling the friction disk by said guide arm, the frictional engagement of said disk being controlled by the change in position of the film when passing through the guide arm to the film take up reel.

3. In a motion picture apparatus, a film take up reel, a variable speed drive for said film take up reel, a pivotally mounted guide arm for the film, the position of one end of said arm being controlled by the position of said film between the apparatus and said take up reel, a lever operated by said guide arm, a variable speed shaft, having its speed controlled by said lever, and means actuated by said shaft for driving said reel.

4. In a motion picture apparatus, a film take up reel, a pivotally mounted guide arm

for the film, a variable speed drive for the film take up reel, a pivoted arm controlled by the movement of said guide arm, a connection between said arm and said variable speed drive, and means actuated by the movement of said arm relative to its connection with said variable speed drive for controlling the speed of said variable speed drive.

- 10 5. In a motion picture apparatus, the combination with a take up reel, a pivotally mounted film guide positioned in the path of travel of the film to said reel, a variable speed drive for said take up reel, means controlled by the increase in diameter of said take up reel for shifting said guide, and means controlled by the shifting of said guide for in turn controlling the speed of rotation of said variable speed drive.

6. In a motion picture apparatus the combination with a take up reel, of means for rotating said take up reel comprising a friction disk, means for rotating said friction disk, a pivotally mounted guide for the film and positioned in the path of travel thereof leading to said take up reel, an arm associated with said guide to move coincidently therewith and means controlled by the movement of said arm for controlling the movement of said friction disk.

Signed at New York city, N. Y., this ninth day of July, one thousand nine hundred and fifteen.

WILLIAM WENDERHOLD.
